UNITED STATES PATENT OFFICE.

CHARLES P. WILLSON, OF SUMMIT POINT, WEST VIRGINIA.

FIRE-ESCAPE.

SPECIFICATION forming part of Letters Patent No. 319,370, dated June 2, 1885.

Application filed March 25, 1885. (No model.)

To all whom it may concern:

Be it known that I, CHARLES P. WILLSON, a citizen of the United States, residing at Summit Point, in the county of Jefferson and State 5 of West Virginia, have invented certain new and useful Improvements in Fire-Escapes, of which the following is a specification.

My invention relates to an improved fire-escape for buildings, designed to enable persons 10 imprisoned in a burning building to escape with safety.

The drawings herewith illustrate the invention.

Figure 1 is a front view of the carriage and 15 suspended block. Fig. 2 is a transverse sectional view of carriage. Figs. 3, 4, and 5 are views of the grip-handle. Fig. 6 is a view of a protecting-cage containing the carriage. Fig. 7 is a top view of the same. Fig. 8 is a view 20 of the escape attached to a building. Fig. 9 is an end view of the traveler on the rail.

A carriage is provided for lowering the person. This carriage consists of two upright bars, A, and a bottom, A', attached thereto. 25 Each end b of the bottom projects sidewise beyond one of the uprights, and said projected ends serve as a rest for the feet of a person. The uprights are connected by rungs b', thus forming a ladder. To lower this carriage a 30 suitable rope, wire cable, or chain, c, is employed. When the carriage is not in use, the said rope is wound on a small reel, B, mounted in bearings at the foot of the uprights. Two 35 grooved clutch-rollers, d e, are mounted at the foot of the uprights, and the rope c passes from the reel B to these rollers, which serve as a friction-clutch. The lower roller, d, has two grooves and the upper one three. Before 40 the rope passes to this friction-clutch it passes through an opening in a cross-bar, f, near the top of the ladder, thence over a roller, f', and then down to and through an opening in a cross-bar, f'', immediately over the friction-clutch. The rope then passes down back of the first 45 groove in the upper roller, e, under said roller, down in front of the first groove in the lower roller, d, under, up, back, and over the lower roller; then up in front of the second groove of the upper roller, over and down, back, un- 50 der said roller, down in front of the second groove of lower roller, under, up, back, and over the said roller, and finally up in front of

the third groove of the upper roller, and from thence through an opening in the lower cross-bar, f'', an opening in the upper cross-bar, f, 55 and through the top plate, f''. From the top plate the rope passes to a suspended block, C, which is provided with a friction-clutch, d e, of the same construction as that on the carriage. From the suspended block the rope designated 60 by c' passes down and through the top plate of the carriage, through the upper cross-bar, f, and through the bottom A'. Its lower end is provided with a ring, c''. The special friction-clutches on the carriage and on the suspended block are to compensate in part for the weight of an average-sized person occupying the carriage. Without them the weight of a person on the carriage would cause it to descend with a speed that would 65 be unsafe. The effect is to nearly offset the weight of a person, or to so restrain the descending movement of the car when a person is on it as to insure its descent at a moderate speed. The rope is provided on that portion 70 which passes from the reel to the opening in the upper cross-bar, f, with a friction grip-handle, D, which is in the form of a tube made in two parts or split longitudinally. Each of the two parts of the grip-handle is lined with 75 leather or rawhide, g, and then the two parts are placed together, with the rope between, as in Fig. 4, and secured by screws h. The screws will regulate the friction or grip of the two parts of the handle D on the rope, and 80 should be so adjusted that the handle will not slip on the rope until a pull has been made thereon of predetermined power—say equal to 85 ten or twenty pounds. Normally the handle D has position just below and in contact with 90 the upper cross-bar, f, and this amount of friction or grip of the handle on the rope is sufficient to prevent the rope from being paid out from the reel, and therefore the carriage will not descend, but will hang suspended. To 95 cause the carriage to descend, the person on it must grasp the grip-handle D when at its position below the upper cross-bar, f, and draw down on it with sufficient force to slip it on the rope, say, for a space of a foot or eighteen inches, then as the rope pays out allow it 100 to go up to the cross-bar, and then again draw down on it. By continuing this operation of slipping the grip-handle the carriage will be

lowered. When the carriage has reached the ground, and the person has alighted, it may be hoisted again for the rescue of another person by grasping the ring c^2 at the end of the 5 rope and pulling thereon. When a person gets on for the second descent of the carriage, the latter is controlled in its downward movement by a person on the ground paying out the rope or allowing it to slip through his 10 hands. The suspended block C is hung from a chain, i, which has a hook, i', attached. This hook may be attached to any convenient place of fastening—such as to a window-sill or an article of furniture like a bedstead in the up- 15 per room of a building—and thereby the block may hang suspended on the outer wall of the building. The hook i', however, may be attached to a traveler or movable eye, F, on a horizontal rail, G, fixed to the front wall or 20 cornice of a building. By this arrangement the suspended block C and escape-carriage may have their position shifted from one point in front of the building to another to meet the exigencies of the case in time of fire. The rail 25 G may be fixed or supported by brackets k in any suitable manner, and the eye F is attached to a block, l, provided with grooved rollers m, which rest on the rail. It will thus be seen that the block and eye may travel along the 30 rail from one end to the other.

The carriage heretofore described may be inclosed in and attached to a cage, H, of sheet metal, or canvas coated with fire-proof paint. The object of the cage is to protect a person 35 while descending from flames that may be issuing from the windows of the building. The carriage A is attached to one side of the cage, and the walls of the cage may be constructed of sheet metal, or canvas made non- 40 combustible. At one side the cage has a door, n, and a rope, p, is attached at one side and near the top of the cage, and hangs down and serves for a person on the ground to draw the cage away from the building, in order that, 45 as the cage is being lowered, it may clear or avoid obstructions on the front of the building. In the present instance the rope p is attached to a chain, p', having each end made fast to an opposite side of the cage. Where 50 the cage is used the rope c from the carriage passes through a leveling-hanger, I, whose function is to maintain the cage in a vertical position when it is drawn away from the building by the rope p. The leveling-hanger consists of a block, I, provided with three sheaves 55 or rollers, q. This block has a flexible connection with the cage. A chain, r, connects one end of this block to a stud, s, projecting up above the top of the cage, and at one side 60 of the cage, and two chains, r', connect the other end of the block to the opposite side of

the top of the cage. That part of the rope c from the carriage passes between the first and second sheaves q, and that part of the rope c' from the suspended block passes between 65 the second and third sheaves. This arrangement of sheave-block having a flexible connection with the cage, and the rope c passing through the sheave-block, will allow of the cage being drawn to one side as much as desired, and yet insure its retaining a level or vertical position. In the case of the cage the end of that part of the rope c' which comes from the suspended block is passed through an opening, t, at the top rim of the cage, on 70 the side opposite that where the carriage is attached. 75

Having described my invention, I claim and desire to secure by Letters Patent of the United States—

1. A fire-escape having in combination a suspended block, C, a carriage having two grooved clutch-rollers, d e, and a lowering-rope, c, passed over and around the said rollers, thence to the suspended block, thence back 85 to the carriage, and provided on that portion which leads to the clutch-rollers with a friction grip-handle, D, as set forth.

2. A fire-escape having in combination a horizontal rail, G, fixed to the front of a building, a traveler-block having grooved rollers to rest on the rail, and an eye, F, a block, C, suspended from the said eye, a carriage having grooved clutch-rollers, a lowering-rope passed first over the said rollers, thence to 95 the suspended block, and thence back to the carriage, and a friction grip-handle, D, on the rope, as set forth.

3. A fire-escape having in combination a suspended block, C, a cage-carriage to protect an escaping person from the flames, a leveling-hanger, I, provided with sheaves and attached above the cage-top by a flexible connection, and a lowering-rope passed from one side of the cage-carriage between the sheaves 105 of the leveling-hanger to the suspended block, thence back between said sheaves to the cage-carriage, and through an opening on the opposite side, as set forth.

4. In a fire-escape, a cage-carriage having above it a sheave-block attached to opposite sides of the cage-top by a flexible connection, in combination with a lowering-rope leading from the cage-carriage and passed through the sheave-block, as set forth.

In testimony whereof I affix my signature in presence of two witnesses.

CHARLES P. WILLSON.
